VOLATILIZER.

1,199,223.

Specification of Letters Patent. Patented Sept. 26, 1916.

Application filed August 24, 1914. Serial No. 858,195.

To all whom it may concern:

Be it known that I, FRANK TEED, a citizen of the United States, residing at Portland, in the county of Multnomah and State of Oregon, have invented certain new and useful Improvements in Volatilizers, of which the following is a specification.

My invention relates to volatilizers for internal combustion engines, and has for its object the production of effective and novel apparatus for the conversion by heat of any suitable liquid fuel such as the heavier hydrocarbons, embracing kerosene, distillate, and the like, into a gas, which with a proper admixture of air, for which my apparatus makes provision, is available for fuel to the engine.

Among the various features of my invention the simplicity of my apparatus as well as its high degree of efficiency resulting in the production of a gas of practically perfect combustibility is important.

In respect to efficiency it may be observed that in apparatus of the class to which my invention belongs, the heat available for the heating of the liquid hydrocarbon or the like is derived from the exhaust products of the combustion which takes place in the engine, and that therefore the means by which the heat from such a source is, in my apparatus, made to do the work of gasification is, distinctively, the important one among all the features of my invention.

What constitutes my invention will be hereinafter specified in detail and succinctly set forth in the appended claims.

In the accompanying drawing, Figure I is a median vertical section of a present preferred form of embodiment of my invention, partially in elevation. Fig. II is a top plan of the gasifier diaphragm detached. Fig. III is a similar view of the air regulator detached. Fig. IV is a bottom plan detached view of the adjustment disk 45 for air regulator and cut off, showing also the directly correlated members. Fig. V is a view of the cut-off diaphragm detached, similar to Fig. II.

Referring to the numerals on the drawing whereon like numerals refer to like parts throughout, 42 indicates the body of my volatilizer. It is preferably made of a single casting embodying double walls defining between them a closed heating jacket 35 that communicates, as through an intake 36,

with a source of heat, and with means of discharge, as through an outlet 37. In practice the intake is adapted and intended operatively to communicate with the exhaust of an internal combustion engine (not illustrated) whose heated products of combustion pass out through the jacket 35 by way of the outlet 37. The casting 42 also preferably includes the shell 11 of a float-valve chamber that is surmounted and securely closed by a head 10 that is secured to the shell 11, preferably by a threaded flange fitting within said shell.

The head preferably carries a coaxial hollow stem 2 that is preferably shouldered at 70 its upper end to accommodate with snug fitment a hollow cap 9 having an oil inlet 1. The cap 9 fits as indicated at 9* upon top of the head 10 to form therewith an oil tight chamber, and is secured in place preferably by a jam nut 8. An annular oblong recess 4 is formed in the contiguous inner walls of the hollow stem 2 and the stud 6 therein, and communicates with the interior chamber of cap 9 as by a duct 3.

The stem 2 is occupied by the downwardly projecting stud 6 which is threaded into the bore of the stem so as to be susceptible of up and down adjustment through its rotative movement. A screw plug 7 is preferably provided for closing the end of said bore above the stud 6.

The lower end of the stud 6 is preferably provided with a duct 5 whose upper end is deflected so as to communicate with the recess 4 at any point of adjustment of the stud 6. The lower end of the duct 5 terminates in a valve seat 13, which is preferably inversely cone shaped to receive with accurate fit a conical valve 14.

The valve 14 is carried upon a float 12, preferably mounted in a spider 15 within a tubular chamber 12* provided for its accommodation coaxially within the float. The float is guided in its rise and fall movements so as to insure proper opening and closing of the valve 14 against its seat 13 by the downwardly projecting end of the stud 5 and an oppositely projecting stud 16 extending coaxially with the stud 6 from the bottom of the shell 11.

The interior of the shell 11 communicates near its bottom as through an oil passage 17, preferably let into the body 42, with the interior of a gas tight chamber 18, which is 110

preferably of the form of a vertically disposed cylinder preferably surrounded from end to end by a coaxial air passage 22 that is surrounded and defined by a vertical portion 5 of the heating jacket 35, distinctively designated as the barrel B. The chamber 18 being of any preferred construction is defined preferably by an outer wall A (which is also the inner wall of the air passage 22) that is 10 made integral with the body 42, and by a preferably removable inner wall or cylinder 21. The chamber 18 being required to be of gas tight construction, to that end its inner and outer walls are united by any suitable means, as for example a threaded joint 22^a, and are surmounted, with close fitment among the three members, by a diaphragm 23. It is immaterial what mode or means 15 of assemblment of the three members which 20 define the chamber 18 are employed so long as they serve to constitute a gas tight chamber.

The union illustrated of the diaphragm 23 with the cylinder 21 by aid of a threaded joint 22^a and of the outer wall A of the chamber 18 and the diaphragm by a ground joint 22^c is presented merely as an example of means suitable for the purpose, it being obvious for instance that the diaphragm 23 30 may be made integral with the cylinder 21, if preferred.

It is in respect to the diaphragm 23 that the principle of my invention involves certain features that are more or less distinctive. Before proceeding to the consideration 35 of such features, it may be observed upon reference to Fig. I, that the diaphragm 23, combined as it is, as by the joint 22^a, with the cylinder 21, effects, in 40 itself and by parts appurtenant to it, complete closure, except for provision to the contrary included within itself, of the barrel B above the air passage 22. The provision to the contrary referred to in the last 45 sentence is found in certain apertures 19, 21^a and 22^a which penetrate the diaphragm 23 from top to bottom, apertures 19 making communication with the chamber 18, apertures 21^a making communication with the 50 interior of the cylinder 21, and apertures 22^a (preferably consisting of marginal recesses in the diaphragm completed as shown by the encompassing barrel B) making communication with the air passage 22 that 55 surrounds the chamber 18. The apertures 19 are distinctively denominated gas ducts, while the apertures 21^a and 22^a are air ducts. The said air ducts are preferably of adjustable capacity and are limited in their 60 number and transverse dimensions for considerations which will presently be made to appear, but should be of sufficient number and extent to afford adequate means of supply of heated air to the gas which issues from the 65 chamber 18 through the gas ducts 19. The

gas ducts are shown (Fig. II) as eight in number, but the precise number is, of course, only a detail. The essential feature in respect to the gas ducts and the diaphragm 23 which accommodates them is that they shall be of sufficient longitudinal extent and of sufficiently minute diameter to qualify them to perform the function of "flash tubes".

By the term "flash tube" I refer to a tube or duct of such minuteness in cross section as will suffice upon the application of a proper degree of heat to convert, instantaneously and in order that its operation may be continued without material reduction of its own heat, a liquid into a gas in passing through it. The term within the definition stated is well understood in the art relating to circulatory liquid heating systems and in other cognate arts.

The conductivity of the air within the barrel B is not sufficient to communicate a volatilizing temperature from the barrel to the diaphragm 23, but a metallic contact of ample area between those members must be provided. In order that the diaphragm 23 shall be of adequate thickness to accommodate a length in the ducts 19 sufficient for the accomplishment of their "flash tube" function, and also to afford the adequate area of metallic contact for supplying to the walls of said ducts the temperature requisite for the continuous performance of that function, it is necessary that the mass of metal in the diaphragm should not be reduced below an ascertainable minimum. 90 What that minimum should be is a question largely of proportions, and no more than a general rule for determining it can be specified herein. Suffice it to say that the ducts 19 should be long enough to detain an attenuated column of liquid in passing through it in so far as to insure upon application of sufficient heat the substantially instantaneous and continuous vaporization as required of the liquid fuel. At the same time the 100 area of contact between the metal of the diaphragm 23 and that of the barrel B should be so great as to insure, through the conductivity of the said metallic contact communication of that degree of heat which 110 the process of vaporization demands. For example, I prefer to make each of the ducts 19 about one one-thousandths of an inch in diameter and of a length which shall confine 115 for a volatilizing interval while passing through it the liquid fuel or hydrocarbon that is already preheated by the heat of the chamber 18. It is probable that both the length and diameter of the ducts could be varied slightly for different hydrocarbons, 120 but I have made no special experiments along that line of investigation further than to ascertain that excessive reduction of the area of contact between the diaphragm 23 and the barrel B results in interruption of 130

the operation of my apparatus. My preference, therefore, in the construction of the diaphragm, is to provide it, as shown in Fig. II, with four apertures 22^a which define between them a number of contact making members C preferably corresponding in number and substantially in transverse extent to apertures 22^a, but the number of apertures and of the contact making members is susceptible of some variation within limits indicated in the last preceding sentence.

In apparatus of the present description provision should be made for control of the flow of gas and of the air supplied thereto. I prefer to provide means therefor in connection with the diaphragm 23 and, specifically, such as are shown in the drawing. The said preferred specific means consists of a flat disk valve 24 which makes a tight slip joint with the top face of the fixed diaphragm 23 against which it rotates. It is provided with a preferably integral hollow stem 24^a which, at its upper end, fits rotatively within a bearing 23^a provided for it in the diaphragm 23, and at its lower end fits, in like manner, within a bearing provided for it in the boss 43 of the body 42 coaxially with the bearings 23^a.

The valve 24 is provided with apertures 21^c located to register, respectively, with apertures 21^a in the diaphragm 23, though the latter are preferably elongated as shown in Fig. II to accommodate a relative adjustment of the valve, hereinafter described. The valve 24 is also provided with apertures 19^a that register, respectively, with the apertures 19 in the diaphragm 23, and which are, for the purposes of adjustment alluded to above, of a greater extent, transversely, than are apertures 19. Such enlargement of transverse extent in the apertures 19^a may be obtained for example, by extending them into arc shaped slots concentric in disposition with the valve disk 24, as shown in Fig. V, but this is a variable detail. The valve 24 is also provided with marginal recesses 22^a which correspond in number and disposition with the recesses 22^a of the diaphragm 23, and which, when the valve is in place within the barrel B, constitute, in the valve, apertures which the encompassing barrel serves to complete. The recesses 22^a define contact making members C^a which in number and disposition correspond to the members C of the diaphragm 23. My preference for making the contour of the valve 24 to correspond with that of the diaphragm 23 is determined by the fact that, by reason of the close juxtaposition of those numbers, they coöperate as one member to effect conduction from the barrel B to the walls of the gas ducts 19 of heat sufficient for the purpose of volatilization as already specified.

I prefer to provide, preferably in connection with the valve 24, means for regulating the air supply to the mixing chamber 39 into which air and gas, passing through the diaphragm 23, are discharged and where they are commingled. To that end I provide a disk regulator 25 whose radius is less than that of the circle about which the apertures 19 and 19^a are ranged, and which is provided with openings 21^b that correspond in number and disposition, and preferably in diameter with the apertures 21^c in the valve 24. Means are provided for setting the regulator 25 so that its openings 21^b shall perfectly or partially register with or completely close the apertures 21^c, whereby the air supply capacity of the said apertures may be regulated to a nicety. Said means preferably consists of a rod 25^a which fits rotatably within the hollow valve stem 24^a and extends from end to end thereof. At one extremity it projects in the shape of a reduced end 25^b to accommodate the regulator 25 which is secured to it by a nut 25^c. At its other extremity it carries in like manner an adjustment disk 30 that is securely fixed to it as by a nut 34.

Between the disk 30 and the end of the boss 43 I provide the hub 29^a of a lever handle 29, fixed to the slightly reduced smooth end of the stem 24^a. The hub is surmounted by a nut 28 that is threaded to the stem 24^a and bears against an annular spring 27 interposed directly between it and the end of the boss 43, with the effect of affording a yielding and adjustable means of securing the valve stem 24^a and its valve 24 in place.

A collar 26 is preferably provided about the end of the boss 43. It is adjustably fixed in place as by an abutment screw 26^a and has a stop lug 26^b that projects in the path of movement of the lever 29. By adjustment of the collar 26 the swing of the lever may be limited as desired, and the cut-off movement of the valve 24 thereby determined and fixed.

The disk 30 is provided as a means for adjustably coupling the valve 24 and the disk 25 together, and that end is accomplished through a direct engagement between the disk 30 secured to the rod 25^a, on the one hand, and the hub 29^a secured to the valve stem 24^a, on the other hand. The said direct engagement is effected by aid of a screw stud 31 projecting from the hub 29^a through an arc shaped slot 33 in the disk 30 and concentric with the disk. A jam nut 32 threaded to the stud 31, affords means for securing the stem 24^a and the rod 25^a as well as their respectively attached members 24 and 25 in any relative positions to which, upon loosening of the nut 32, they may be adjusted. After the nut 32 is set against the disk 30 the members 24 and 25 work together as one upon manipulation of the lever 29.

- Supply of air to the interior of the jacket 35 is regulated by suitable means such for example as a valve 38 mounted near the air intake 29.
- 5 The mixing chamber 39 is located above the valve 24 and may be no more than the unobstructed end of the interior of the barrel B. As shown in Fig. I of the drawing it is slightly constricted by the throat of a 10 suitable union 40 which I prefer to employ as a means for attaching my volatilizer in place in service. The union 40 is characterized by a petticoat flange 43 depending from a web flange 44. The end of the flange 43 fits snugly within the collar 42^a of the body 42 and is securely held in position therein but with convenient detachability, as by aid of a series of abutment screws 41 that penetrate the collar 42^a from the side and whose 15 ends engage the outside of flange 43.
- The operation of my apparatus may be clearly understood from the foregoing in view of the following brief description. The shell 11 with its parts appurtenant and 20 the mechanism for control of liquid fuel supply which my apparatus like other devices for a generally similar purpose includes is preferably provided. By it or other suitable means a suitable hydrocarbon or other 25 liquid, is supplied through the oil inlet 1 to the interior of the shell 11 that communicates with the chamber 18, and is, by the operation of the float 12 and its valve 14, maintained therein at a substantially constant 30 variably determinate level. From the chamber the liquid fuel, passing through the oil passage 17, enters the chamber 18 whence it issues through the diaphragm 23 whose walls are heated by the discharge of the 35 heated products of combustion from the engine (not illustrated) as they pass from the intake 36 to the outlet 37 through the heating jacket 35 of the body 42 of the vaporizer. The heat so derived is communicated to the 40 chamber 18 at such a degree as to raise the temperature of the oil therein to a high degree, but by reason of the direct metallic contact between the barrel B and the diaphragm 23, located, as such points of contact are, directly opposite the intake 36, a 45 higher temperature sufficient to volatilize the heated oil therein is communicated to the walls of the gas ducts 19 which operate as specified with "flash tube" upon the oil as it passes through them. The result is that a continuous flow of gas is discharged from the ducts into the mixing chamber 39 where it is commingled with heated air supplied through the air ducts of the diaphragm 23. 50 The means for regulating the supply of said air have been already described as well as the means for shutting off the flow of both air and gas by manipulation of the lever 29.
- What I claim is:
- 65 1. In a volatilizer for internal combustion engines, the combination with a body provided with means for the discharge through it of the heated products of combustion from an engine, of a gas tight chamber defined within said body and adapted when in service for operative communication with the engine, means of liquid fuel supply to the said chamber, and a member in heat conductive contact with said body and provided with ducts of flash tube effect that afford exclusive means of escape for the contents of said chamber, whereby in passing through them a flow of liquid fuel supply to the chamber is converted into a fixed gas and issues from the ducts in continuous supply. 70
2. In a volatilizer for internal combustion engines, the combination with a body provided with an air passage adapted to communicate with an engine and including a barrel, of a chamber defined within said body and located within the barrel so as only partially to obstruct the air passage, and provided with gas ducts adapted to discharge the contents of the chamber with flash tube effect into a commingling chamber provided in the air passage, means of heating the walls of said ducts to a gasifying temperature, and means of liquid fuel supply to said chamber. 75
3. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 80
4. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 85
5. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 90
6. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 95
7. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 100
8. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 105
9. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 110
10. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 115
11. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 120
12. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 125
13. In a volatilizer for internal combustion engines, the combination with a body provided with an air passage adapted to communicate with an engine and including a barrel, of a chamber defined within said body and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber. 130

gas and air discharged through the diaphragm, and means for regulating the air supplied through the air passage to the commingling chamber.

5. In a volatilizer for internal combustion engines, the combination with a body provided with an air passage adapted to communicate with an engine and including a barrel, of a chamber defined within said body, and located within the barrel so as only partially to obstruct the air passage, a diaphragm in contact with the barrel, means of heating the diaphragm from the products of combustion of the engine, means of communication of the air passage through the diaphragm, gas ducts in the diaphragm communicating with and adapted to discharge the contents of said chamber with flash tube effect, a commingling chamber provided in the air passage to receive the gas and air discharged through the diaphragm, and means for regulating the air supplied through the air passage to the commingling chamber said last named means comprising a movable valve apertured correspondingly to the diaphragm and in operative juxtaposition to the diaphragm.
6. In a volatilizer for internal combustion engines, the combination with a body provided with an air passage adapted to communicate with an engine and including a barrel, of a chamber defined within said body and located within the barrel so as only partially to obstruct the air passage, means of heating the diaphragm from the products of combustion of the engine, a diaphragm closing the barrel and the chamber, air ducts in the diaphragm establishing communication between the two portions of air passage separated by the diaphragm, gas ducts in the diaphragm communicating with and adapted to discharge the contents of said chamber with flash tube effect, a commingling chamber provided in the air passage to receive the gas and air discharged through the diaphragm, and means of liquid fuel supply to said chamber.
7. In a volatilizer for internal combustion engines, the combination with a body provided with an air passage adapted to communicate with an engine and including a barrel, of a chamber defined within said body and located within the

barrel so as only partially to obstruct the air passage, means of heating the diaphragm from the products of combustion of the engine, a diaphragm closing the barrel and the chamber, air ducts in the diaphragm establishing communication between the two portions of air passage separated by the diaphragm, gas ducts in the diaphragm communicating with and adapted to discharge the contents of said chamber with flash tube effect, a commingling chamber provided in the air passage to receive the gas and air discharged through the diaphragm, means of liquid fuel supply to said chamber, a valve provided with apertures to correspond with those in the diaphragm and juxtaposed to the diaphragm with slip joint effect, and means for actuating the valve.

8. In a volatilizer for internal combustion engines, the combination with a body provided with an air passage adapted to communicate with an engine and including a barrel, of a chamber defined within said body and located within the barrel so as only partially to obstruct the air passage, means of heating the diaphragm from the products of combustion of the engine, a diaphragm closing the barrel and the chamber, air ducts in the diaphragm establishing communication between the two portions of air passage separated by the diaphragm, gas ducts in the diaphragm communicating with and adapted to discharge the contents of said chamber with flash tube effect, a commingling chamber provided in the air passage to receive the gas and air discharged through the diaphragm, means of liquid fuel supply to said chamber, a valve provided with apertures to correspond with those in the diaphragm and juxtaposed to the diaphragm with slip joint effect, a regulator apertured to correspond to the valve, means for adjustably uniting the regulator and valve, and means for actuating the valve and regulator as one member.

In testimony whereof, I have hereunto signed my name to this specification in the presence of two subscribing witnesses.

FRANK TEED.
